UNITED STATES PATENT OFFICE

155,635

DESIGN FOR A COMBINATION OIL COOKING AND IMPLEMENT HEATING STOVE

Sam Springer, Chicago, Ill., assignor to 300
Chemical Co., Chicago, Ill., a corporation of
Illinois

Application May 26, 1948, Serial No. 146,625

Term of patent 7 years

(Cl. D81—10)

To all whom it may concern:

Be it known that I, Sam Springer, a citizen of the United States and resident of Chicago, in the county of Cook and State of Illinois, have invented a new, original, and ornamental Design for a Combination Oil Cooking and Implement Heating Stove, of which the following is a specification, reference being had to the accompanying drawing, forming a part thereof.

Fig. 1 is a front elevational view of a combination oil cooking and implement heating stove, showing my new design.

Fig. 2 is a top plan view of the same.

Fig. 3 is a side elevational view of the same.

The rear portion of same, not shown, is substantially plain.

I claim:

The ornamental design for a combination oil cooking and implement heating stove, substantially as shown and described.

SAM SPRINGER.
